UNITED STATES PATENT OFFICE

JOHN B. DYER, OF ANDERSON, INDIANA, ASSIGNOR TO DELCO-REMY CORPORATION, OF DAYTON, OHIO, A CORPORATION OF DELAWARE

ENGINE-STARTING APPARATUS

Application filed January 11, 1928. Serial No. 245,886.

This invention relates to engine starting apparatus and particularly to the type of apparatus which comprises a shaft driven by an electric motor and connectible with the gear of an engine to be started by means including a pinion and provisions whereby the pinion will be automatically demeshed from the engine gear when the engine becomes self-operative.

One of the objects of the present invention is to provide for substantially meshing the pinion with the engine gear before the electric motor is operated in order to minimize the liability of breaking gear teeth. In the present invention, this object is accomplished by providing a sleeve which slides along the shaft and is connected with a helically splined portion thereof so that the sleeve will be caused to rotate relative to the shaft as it is moved longitudinally. The pinion also slides along the shaft and is connected with the sleeve by longitudinal splines. Hence, if the ends of the pinion teeth abut the ends of the engine gear teeth before meshing takes place, longitudinal motion of the sleeve will produce rotation of the pinion into meshing registration with the engine gear. The sleeve is moved longitudinally by a manually operated actuator which is automatically disconnected from the sleeve before the engine becomes self-operative in order that the pinion and sleeve will be free to move away from the engine gear, the instant the engine becomes self-operative and regardless of whether the operator fails to release the sleeve actuator. Preferably, the sleeve actuator is automatically disconnected from the sleeve during the engine cranking operation.

Further objects and advantages of the present invention will be apparent from the following description, reference being had to the accompanying drawings, wherein a preferred form of embodiment of the present invention is clearly shown.

In the drawings:

Fig. 1 is a fragmentary longitudinal sectional view of an engine-starting apparatus embodying the present invention and showing the apparatus in normal condition when the pinion is demeshed from the engine gear.

Fig. 2 is a view similar to Fig. 1, showing the apparatus at the instant the pinion is in meshing registration with the engine gear.

Fig. 3 is a view of the apparatus showing the pinion meshed with the engine gear and the motor switch open.

Fig. 4 is a fragmentary cross sectional view on the line 4-4 of Fig. 1.

Fig. 5 is a fragmentary sectional view on the line 5-5 of Fig. 1.

Fig. 6 is a fragmentary sectional view on the line 6-6 of Fig. 7.

Fig. 7 is a longitudinal sectional view of the engine starting apparatus in condition for cranking the engine.

Fig. 8 is a view similar to Fig. 7, showing the condition of the apparatus after the engine becomes self-operative and before the operator releases the pedal operated mechanism which controls the apparatus.

The engine starting apparatus comprises a motor driven shaft 20 supporting the motor armature 21 which revolves within a field frame 22 which is attached to a mounting bracket and gear housing 23 which is adapted to be secured to the flywheel gear housing of the engine to be started. The left-hand end of the shaft 20 is supported in the usual manner by a bearing not shown attached to the field frame 22 and the right-hand end of the shaft 20 is journalled in a bearing 24 supported by the housing 23. The shaft 20 is provided with helical splines 25 along which the hub 26 of a shifter sleeve 27 is slidable, the hub 26 having internal helical splines 28 cooperating with the splines 25 of the shaft. In this way the shaft and shifter sleeve are drivingly connected and the shifter sleeve is caused to rotate as it moves endwise along the shaft 20. A pinion 30 is movable along the shaft into mesh with a gear 31 connected with the engine to be started. Pinion 30 is connected with the sleeve 27 by providing the pinion with splines 32 which are received by suitable notches provided in the internal annular flange 33 of the sleeve. A spring 34 located within the sleeve 27 and pressing at one end against the sleeve and at the other end against the pinion, tends to maintain the normal relation of the sleeve and pinion,

90
95
100

as shown in Fig. 1. Separation of the sleeve and pinion is prevented by a wire split ring 35 which is received by a suitable groove in the hub of the pinion. The sleeve 27 is provided with holes 36 in order that suitable tools may be inserted for manipulating the split ring 35 in order to force it into the groove or remove it from the groove of the pinion.

10 While the engine gear 31 is being driven by the pinion 30 as shown in Fig. 7, the shifter sleeve 27 will be thrust against the pinion 30 owing to the helical splined connection between the shaft 20 and the sleeve. The end thrust of the pinion is delivered to the shaft 20 through a wire split ring 37 which is received by a groove 38 in the shaft 20. The end thrust of the shaft 20 is delivered to the frame 23 by providing the shaft with a shoulder 39 which abuts a collar 40 which is in engagement with a plane surface 41 provided by the frame 23.

15 The mechanism for moving the shifter sleeve and pinion endwise toward the engine gear comprises a pedal 50 which extends through the floorboard 51 of an automobile and is connected with a lever 52 pivoted upon a screw 53 attached to the frame 23. The lever 52 carries an extension 54 located in the path of movement of the head 55 of a plunger 56. A spring 57 which is located within a recess 58 of the frame 23, and which surrounds the plunger 56, urges the head 55 against the lever extension 54 in order 20 to urge the lever 52 into normal position, shown in Fig. 1, in which a lug 59 of the lever engages a portion of the frame 23. The bolt 53 pivotally supports a lever 60 in such a manner that the lever 60 may also move laterally into an inclined position 60^a shown 25 in Figs. 4 and 6. The lever 60 carries at its lower end a sleeve actuating member or roller 61 which is adapted to be received by grooves 62 which are located between spiral ridges 63 provided in the end face 64 of the sleeve 27. The lever 60 is provided at its upper end with a lug 65 which is received by a slot 66 in the lever 52. A coil spring 67 located around the screw 53, has an end 68 bearing against the 30 lever 60 and an end 69 received by holes 70 in the lever 52. The spring 67 is biased in a manner such as to urge the lever 60 counterclockwise relative to the lever 52 so that normally as shown in Fig. 1, the lug 65 bears 35 against the left-hand end of the surface of the lever 52 which defines the slot 66. The turns of the spring 67 are spaced and when the spring is located between the head of the screw 53 and one side of the lever 60, as shown 40 in Fig. 4, the spring will be in a state of compression in order to urge the lever 60 sideways against the lever 52.

45 The lever 52 carries a stud 71 adapted to engage the plunger or actuator 72 of a switch 65 for controlling the motor which drives the

shaft 20. The switch is located within a case 73 attached by screws 74 to the motor frame 22. A spring 75 located between the actuator 72 and the case 73 tends to hold the actuator in switch open position.

70 The operation of the invention is as follows:

To start the engine the operator presses the pedal 50 in order to cause the pinion to move from the position shown in Fig. 1 to the gear meshing position shown in Fig. 3. In case the pinion teeth abut the engine gear teeth before meshing takes place, endwise movement of the pinion will be arrested but the pinion may be rotated into meshing registration with the engine gear by continuing the endwise movement of the sleeve 27 toward the engine gear. As the sleeve moves it will rotate relative to the shaft 25 and will turn the pinion sufficiently to cause its teeth to be located in alignment with the tooth spaces of the engine gear. The condition of the engine starting apparatus at the instant the pinion has been brought into meshing registration with the engine gear is shown in Fig. 2. It will be noted that the sleeve has been moved relative to the pinion and that the spring 34 has been compressed. The direction of rotation of the sleeve relative to the shaft 23 is clockwise as viewed in Fig. 5. Hence there is no tendency for the lever 60 to move laterally away from the sleeve.

90 After gear meshing registration of the pinion has been effected, the pinion will move from the position shown in Fig. 2 to that shown in Fig. 3, the spring 34 expanding in order to produce this movement. By continuing to press the pedal 50 the operator will cause the stud 71 to engage the switch actuator 72 in order to close the motor switch. Then the shaft 20 will rotate in order to move the sleeve 27 into the pinion driving position shown in Fig. 7. A portion of the movement of the sleeve 27 from the position shown in Fig. 3 to that shown in Fig. 7 is effected during the movement of the lever 52 into position for closing the motor switch, and the latter portion of the movement of the sleeve is effected by the operation of the motor. During the cranking of the engine by the motor, the sleeve 27 will remain in the position shown in Fig. 7 and will maintain the spring 34 compressed independently of any action produced by the lever 60. Therefore the present invention provides for disconnecting the lever 60 from the sleeve 27 during the engine cranking operation so that the instant the engine becomes self-operative, the pinion may be demeshed regardless of the location of the lever 60 and the sleeve actuating roller 61. This automatic disconnection is effected by the cooperation of the helically arranged ridges 63 and the roller 61. The direction of rotation of the shaft 20 during engine cranking is counterclockwise as viewed in Figs. 5 and 6.

Hence, one of the ridges 63 will cam the roller 61 from the position shown in Fig. 5 to that shown in Fig. 6. After the roller 61 has been cammed out to the edge of the face 64 of the sleeve 27, the spring 67 will be released to change the relative location of the levers 60 and 52 from the relation shown in Fig. 3 to that shown in Fig. 7. Therefore, the roller 61 will be located alongside a cylindrical surface 80 of the sleeve 27 in opposition to the pressure of the spring 67 which is exerted axially of the screw 53. When the engine becomes self-operative, the sleeve 27 and the pinion 30 will be moved from the position shown in Fig. 8 regardless of whether the operator has released the pedal 50. Although the roller 61 remains in the positions shown in Figs. 7 and 8, the sleeve 27 is free to move endwise. During its movement from that position shown in Fig. 7 to that shown in Fig. 8 its cylindrical side surface will be yieldingly engaged by the roller 61. This yielding engagement may be effective in maintaining the sleeve in normal position in order that the pinion may not be remeshed with the engine gear although the motor continues to run. The remeshing of the pinion may be also hindered by providing the sleeve with a groove 81 for receiving a plunger 82 which slides radially of the shaft within a sleeve 83 threaded into a side wall of the frame 23 as shown in Figs. 2 and 8. A plug 84 which closes one end of the sleeve 83 retains a spring 85 which urges the plunger 82 toward the shaft. When the pedal 50 is released, levers 52 and 60 will be moved due to the action of the spring 57 from the position shown in Fig. 8 to that shown in Fig. 1. During the clockwise rotation of the lever 60, the roller 61 will slide along the cylindrical side of the sleeve 27 and will be urged by the spring 67 from the position shown in Fig. 6 to that shown in Fig. 5. Thus the roller 61 is located again for engagement with the end face 64 of the sleeve.

The accidental drifting of the pinion into mesh with the engine gear while the engine is running is hindered also by the engagement of the roller 61 with a flange 90 provided by the sleeve 27.

While the form of embodiment of the present invention as herein disclosed, constitutes a preferred form, it is to be understood that other forms might be adopted, all coming within the scope of the claims which follow.

What is claimed is as follows:

1. Engine starting apparatus comprising, in combination, a motor; a shaft operated by the motor; a pinion movable longitudinally of the shaft into mesh with an engine gear; a rotatable shifter member movable coaxially with said pinion; means for drivably connecting the shifter member and pinion and permitting relative movement axially of the pinion between said members;

means for so connecting the shifter member and shaft that movement of the member longitudinally of the shaft will effect rotation of the member; a spring for imparting movement from the shifter member to the pinion in a direction to mesh the pinion; a manually operable actuator for moving said member; and means for automatically disconnecting the actuator from the member before the engine starts.

2. Engine starting apparatus according to claim 1 in which the means which automatically disconnects the actuator from the rotatable shifter member is operated in response to the operation of the motor.

3. Engine starting apparatus according to claim 1 in which the means which automatically disconnects the actuator from the rotatable shifter member comprises a cam carried by the rotatable shifter member and cooperating with a part moved by the actuator longitudinally against the rotatable member and mounted so as to be moved by the cam laterally away from the rotatable member.

4. Engine starting apparatus comprising, in combination, a motor; a helically splined shaft operated by the motor; a shifter sleeve drivingly connected by said splines with the shaft; a pinion slidable along the shaft into mesh with an engine gear and drivingly connected with the sleeve by means permitting endwise movement of the sleeve relative to the pinion; a spring for imparting movement from the sleeve to the pinion in a direction to mesh the pinion; a manually operable actuator for moving the sleeve; and means for automatically disconnecting the actuator from the sleeve before the engine starts.

5. Engine starting apparatus according to claim 4 in which the actuator is automatically disconnected from the sleeve by means responsive to the operation of the motor.

6. Engine starting apparatus according to claim 4 in which the sleeve carries a cam which cooperates with a follower element to move the same laterally away from the sleeve when the motor operates, the follower element being connected with the actuator so as to move longitudinally of the shaft against the sleeve and being mounted so as to permit movement laterally with respect to the sleeve.

7. Engine starting apparatus comprising, in combination, a motor; a helically splined shaft driven by the motor; an endwise movable and rotatable shifter member engaging said splines; a pinion adapted to move endwise into mesh with a gear of an engine to be started; driving connections between the pinion and shifter member providing limited endwise movement of the pinion relative to said member; manually operable means for moving said shifter member endwise and causing it to rotate; and a spring for transmitting meshing movement from said shifter member to the pinion in order to urge the

pinion endwise toward the engine gear with yielding pressure.

8. An engine starter drive comprising, in combination, a rotatable driving member adapted to move axially into driving connection with a member of an engine to be started; means including a manually operated actuator and a spring for transmitting motion from the actuator to the driving member in order that the driving member may be yieldingly urged against the engine member in case the driving member collides with the engine member before becoming drivingly connected therewith; means cooperating with the actuator for causing the driving member to rotate while being yieldingly pressed against the engine part; means for automatically disconnecting the actuator from the driving member before the engine starts; and means for automatically disconnecting said members when the engine starts.

9. An engine starter drive comprising, in combination, a rotatable driving member adapted to move axially into driving connection with a member of an engine to be started; means including a manually operated actuator and a spring for transmitting motion from the actuator to the driving member in order that the driving member may be yieldingly urged against the engine member in case the driving member collides with the engine member before becoming drivingly connected therewith; means cooperating with the actuator for causing the driving member to rotate while being yieldingly pressed against the engine part; a starting motor for operating the driving member; means responsive to the operation of the motor for automatically disconnecting the actuator from the driving member before the engine starts; and means for automatically disconnecting said members when the engine starts.

10. An engine starter drive comprising, in combination, a rotatable drive shaft; a rotatable drive-connecting-member adapted to be moved longitudinally of the shaft into driving connection with a part of an engine to be started; an intermediate drive device movable longitudinally of the shaft; means so connecting the shaft and device that relative longitudinal movement is accompanied by relative rotary movement; means connecting the drive-connecting-member and intermediate device so as to permit relative longitudinal movement between them; a spring located between the intermediate drive device and the drive-connecting-member for normally maintaining a certain normal longitudinal relation between the member and device; means having a manually operated actuator for moving the intermediate device and drive-connecting-member toward the engine part in order to connect said member and part; and for causing the intermediate

drive device to rotate the drive-connecting-member while the latter is yieldingly pressed against the engine part; and means for automatically disconnecting the actuator.

11. An engine starter drive comprising, in combination, a rotatable drive shaft; a rotatable drive-connecting-member adapted to be moved axially along the shaft into driving connection with a part of an engine to be started; an intermediate drive sleeve movable axially along the shaft, and having helical spline connections with the shaft and straight longitudinal spline connections with the member; a spring located between the intermediate drive device and the drive-connecting-member for normally maintaining a certain normal longitudinal relation between the member and device; means having a manually operated actuator for moving the intermediate device and drive-connecting-member toward the engine part in order to connect said member and part; and means for automatically disconnecting the actuator.

12. Engine starting apparatus comprising, in combination, a motor; a shaft driven thereby; means for connecting the shaft with the gear of an engine to be started and comprising a pinion movable endwise into mesh with the engine gear and provisions whereby the pinion will be automatically demeshed when the engine starts, said connecting means including an intermediate endwise movable shaft so connected with the motor shaft that endwise movement of the intermediate shaft will produce rotation thereof relative to the motor shaft, and means connecting the intermediate shaft and pinion and providing for relative longitudinal movement between them; a spring rotated between the intermediate shaft and the pinion adapted to urge the pinion yieldingly against the gear; manually operated means for rendering the spring operative yieldingly to press the pinion against the gear in case of abutment before meshing, and for moving the intermediate shaft endwise in order to rotate the pinion while it is yieldingly pressed against the gear, said manually operable means having an actuator; and means for automatically disconnecting the actuator from the manually operated means before the engine starts.

13. Engine starting apparatus comprising, in combination, a motor; a shaft operated thereby; a pinion movable endwise along said shaft into mesh with an engine gear; a sleeve drivingly connected with the shaft in such manner that relatively longitudinal movement between the sleeve and shaft is accompanied by relative rotary movement between them; driving connections between the sleeve and pinion providing for a limited amount of relative longitudinal movement between them, and transmitting to the pinion substantially only rotary motion until the

lost motion between the sleeve and pinion is taken up; a spring located between the sleeve and the pinion for yieldingly urging the pinion against the gear while the pinion is being turned by the sleeve; manually operated means for moving the sleeve in order to mesh the pinion with the gear; and means for automatically rendering the manual means inoperative to prevent demeshing of the pinion by the starting of the engine.

14. Engine starting apparatus comprising, in combination, a motor; a shaft operated thereby; a pinion movable endwise along said shaft into mesh with an engine gear; a pinion shifter movable along the shaft and connected with the shaft in such manner that endwise movement of the shifter is accompanied by rotation thereof; lost motion connections between the shifter and pinion permitting limited longitudinal movement of the shifter relative to the pinion in case endwise movement of the pinion is arrested, whereby rotary motion only will be imparted by the shifter to the pinion until the longitudinal lost motion is taken up; a spring for transmitting motion from the shifter endwise to the pinion whereby the pinion will be yieldingly pressed against the engine gear while being rotated prior to meshing; manually operable means for moving the shifter and including an actuator; automatic means for disconnecting the actuator from the shifter before the engine starts; and automatic means for disconnecting the pinion from the gear when the engine starts.

15. Engine starting apparatus comprising, in combination, a motor; a pinion connected with the motor and movable axially into mesh with a gear of an engine to be started; a shifter movable axially of the pinion; a spring transmitting a pinion-meshing movement from the shifter to the pinion; manual means for moving the shifter and causing it to turn; means transmitting rotary movement from the shifter to the pinion while permitting relative longitudinal movement between them; means causing the pinion to be automatically demeshed from the gear when the engine starts; and means automatically disconnecting the manual means from the shifter before the engine starts.

16. Engine starting apparatus comprising, in combination, a motor; a helically splined shaft driven by the motor; a pinion movable along said shaft into mesh with a gear of an engine to be started; a shifting sleeve engaging the splines of said shaft and having a longitudinal spline connection with the pinion; a spring enclosed by the sleeve and located between the sleeve and pinion for holding them in extended relation; and manually operable means for moving the sleeve.

17. Engine starting apparatus comprising, in combination, a motor; a helically splined shaft driven by the motor; a pinion movable

along said shaft into mesh with a gear of an engine to be started; a shifting sleeve engaging the splines of said shaft and having an internal annular flange notched to receive longitudinal splines provided by the pinion; a spring enclosed by the sleeve and located between the sleeve and pinion for holding them in extended relation; and manually operable means for moving the sleeve.

In testimony whereof I hereto affix my signature.
